UNITED STATES PATENT OFFICE

GEORGE A. JORDAN, OF NEW YORK, N. Y., ASSIGNOR OF ONE-THIRD TO WILLIAM H. JORDAN AND ONE-THIRD TO CHRISTOPHER C. JORDAN, BOTH OF BROOKLYN, NEW YORK.

METAL MOLDING.

1,113,559.

Specification of Letters Patent. Patented Oct. 13, 1914.

Application filed November 7, 1912. Serial No. 729,936.

To all whom it may concern:

Be it known that I, GEORGE A. JORDAN, a citizen of the United States, and a resident of the borough of Brooklyn, county of 5 Kings, city and State of New York, have invented a certain new and useful Metal Molding, of which the following is a specification.

The objects that I have in view are to produce a lasting and fire-proof molding for 10 supporting and inclosing electric wires. This molding is made permanent and fire-proof, while at the same time cheap and easily attached, by being made of sheet 15 metal, formed to proper shape, with a sheet metal capping.

A further object is to produce a molding in which the capping makes a very close fit with the body of the molding, so that dust 20 and moisture are excluded, and no fire can escape in the event of short circuiting of the wires within the molding.

These and further objects will more fully appear from the following specification and 25 accompanying drawings, considered together or separately.

In the drawings: Figure 1 is a perspective view of a portion of a molding, including the capping, made according to my invention. Fig. 2 is a sectional view of the same, taken on the line 2—2 of Fig. 1. Fig. 3 is a similar view, taken on the line 3—3 of Fig. 1. Fig. 4 is a perspective view of a capping, showing a modification. Fig. 5 is a sectional view 35 of a molding with the capping, shown in Fig. 4, in place. Fig. 6 is a perspective view, of a portion of a capping, showing a further modification. Fig. 7 is a sectional view 40 of a molding showing the capping, illustrated in Fig. 6, in place. Fig. 8 is a side elevation of a molding with capping removed, showing a modification. Fig. 9 is a sectional view thereof, taken on the line 45 9—9 of Fig. 8. Fig. 10 is a sectional view of the molding shown in Fig. 9, with the capping in place; and Fig. 11 is a sectional view of still another modification.

In all of the views, like parts are designated by the same reference characters.

50 In carrying out my invention, according to one embodiment thereof, I make a molding 1, of sheet metal. This molding may be stamped or rolled to shape. It is formed with an edge groove 2, 2, on each side. In

addition to the groove, it has a side flange 3, 3, on each side. The parts are conveniently made by means of a rolling operation, the sides of the molding being bent double, so that the edge groove is made at the same time that the side flange is formed. The metal is first creased, and the parts bent backward, thus forming the edge of the molding. The metal is then further creased, and bent back, but at a slight distance from the first creased portion, thus forming the edge groove. The second creasing will form the side flange.

The molding is provided with holes 34, for the passage of screws, nails or other fastening means. The capping 4 is preferably made of sheet metal. It is formed with flanges 5, 5, which extend throughout its length. The flanges are so deep that they extend to the bottom of the edge grooves, so that a close fit between capping and molding is produced. The width of the edge grooves should be such that a close fit is produced with the side flanges of the capping.

The capping may be attached to the molding in a variety of ways. As shown in Figs. 1, 2 and 3, the capping is provided with a number of fastening clips 6, disposed at intervals on the capping. These clips are preferably made of flexible sheet metal. They have flexible end pieces 7, 7, which may be distorted, so as to engage with the side flanges 3, 3, of the molding. The clips may be secured to the capping 4, by means of rivets 8. Fig. 3 shows the position of the capping and clips before the latter are distorted. Fig. 2 shows the same parts, with the clips distorted to final shape. The ends 7, 7, are bent around the side flanges 3, 3, drawing the flanges 5, 5, into the edge grooves 2, 2, and holding the capping in place. These clips will not only hold the capping in place, but will support the weight of the wires contained within the molding.

Figs. 4 and 5 illustrate a modification in which the clips are integrally formed at 9, 9, with the capping. The capping should then be made of some distortable material.

Figs. 6 and 7 illustrate a modification in which the clip is in the form of a button 10, supported upon a pivot 11. The outer face of the head of the pivot is notched, for the

application of a screw driver, so that the button can be turned, to engage with inner flanges 12, formed in the molding.

Figs. 8, 9 and 10 illustrate a modification 5 in which the fastening means is in the form of clips, 13, integrally formed upon the molding. These clips are then bent to engage with the capping, as shown in Fig. 10.

Fig. 11 illustrates a modification of the 10 structure illustrated in Figs. 1, 2 and 3. The clips 6 are loosely applied to the capping, and are not secured thereto, but supported by their engagement with the molding.

Having now described my invention, what 15 I claim as new, and desire to secure by Letters Patent, is:—

1. A metal molding, having side flanges and edge grooves, the sides of the grooves 20 being substantially parallel to the side flanges of the molding, in combination with a metal capping, having flanges which enter and lie within the edge grooves of the molding, and fastening means for engaging the 25 capping with the molding.

2. A metal molding, having integral side flanges and edge grooves, the sides of the grooves being substantially parallel to the side flanges of the molding, in combination 30 with a metal capping, having flanges which enter and lie within the edge grooves of the molding, and fastening means, distortable after the capping is in place, to hold the latter in engagement with the molding.

3. A metal molding, having integral side 35 flanges, and edge grooves, the sides of the grooves being substantially parallel to the side flanges of the molding, in combination with a metal capping, having flanges which enter and lie within the edge grooves of the 40 molding, and a fastening clip, with a flexible portion, capable of being bent around the side flanges to hold the capping in place.

This specification signed and witnessed this second day of November, 1912.

GEORGE A. JORDAN.
